(57) **CLAIM**

The ornamental design for a water-discharge sprinkler, as shown and described.

DESCRIPTION

FIGS. 1 to 7 show a water-discharge sprinkler according to a first embodiment of our new design.

FIG. 1 is a top plan view of the water-discharge sprinkler according to the first embodiment;

FIG. 2 is a perspective view of the water-discharge sprinkler shown in FIG. 1 from an upper front right side of the water-discharge sprinkler shown in FIG. 1;

FIG. 3 is a rear view of the water-discharge sprinkler shown in FIG. 1;

FIG. 4 is a front view of the water-discharge sprinkler shown in FIG. 1;

FIG. 5 is a right side view of the water-discharge sprinkler shown in FIG. 1;

FIG. 6 is a left side view of the water-discharge sprinkler shown in FIG. 1; and

FIG. 7 is a bottom view of the water-discharge sprinkler shown in FIG. 1.

In the first embodiment, surface contour is illustrated with lines with double dashes and with straight lines at some contour transitional positions.

Second Embodiment

FIGS. 8 to 14 show a water-discharge sprinkler according to a second embodiment of our new design.

FIG. 8 is a top plan view of the water-discharge sprinkler according to the second embodiment;

FIG. 9 is a perspective view of the water-discharge sprinkler shown in FIG. 8 from an upper front right side of the water-discharge sprinkler shown in FIG. 8;

FIG. 10 is a rear view of the water-discharge sprinkler shown in FIG. 8;

FIG. 11 is a front view of the water-discharge sprinkler shown in FIG. 8;

FIG. 12 is a right side view of the water-discharge sprinkler shown in FIG. 8;

(Continued)

FIG. 13 is a left side view of the water-discharge sprinkler shown in FIG. 8; and

FIG. 14 is a bottom view of the water-discharge sprinkler shown in FIG. 8.

In the second embodiment, surface contour is illustrated with lines with double dashes and with straight lines at some contour transitional positions.

Third Embodiment

FIGS. 15 to 16 show a water-discharge sprinkler according to a third embodiment of our new design. This third embodiment is a variation of the second embodiment, and other views of this third embodiment are like other views of the second embodiment. FIGS. 15 and 16 also show a preferred color scheme according to the third embodiment.

FIG. 15 is a perspective view of the water-discharge sprinkler according to the third embodiment from an upper left front side of the Water-Discharge Sprinkler of the third embodiment; and,

FIG. 16 is a bottom perspective view of the water-discharge sprinkler shown in FIG. 15 from a lower right front side of the water-discharge sprinkler shown in FIG. 15.
